(57) **CLAIM**

The ornamental design for a futsal goal, as shown.

DESCRIPTION

FIG. 1 is a perspective view of a futsal goal showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is an enlarged view of the portion 8 shown in FIG. 6.

The short-dash broken lines depict portions of the article that form no part of the claimed design and the long-dash broken lines indicating an enlargement portion of the design form no part of the claimed design.

1 Claim, 7 Drawing Sheets
